P. W. THAYER

SOOT RECEPTACLE

Filed Dec. 14, 1922

INVENTOR.
PAUL W. THAYER.
BY HIS ATTORNEY.

James F. Williams

UNITED STATES PATENT OFFICE.

PAUL W. THAYER, OF MINNEAPOLIS, MINNESOTA.

SOOT RECEPTACLE.

Application filed December 14, 1922. Serial No. 606,839.

This invention relates to a device adapted to be attached to a boiler or hot water furnace to collect soot and dirt removed from the inside thereof. The device is particularly designed for collecting soot and dirt removed from the cleanout or flue door of a common type of heating boiler or furnace used in buildings. In such boilers and furnaces it is frequently necessary and desirable 5 to clean and scrape off the soot which collects on the flue walls and hot water chambers. Such cleaning is necessary to an efficient operation of the heating plant and is recommended and urged by the builders of 10 boilers and furnaces. When such soot and dirt is removed it has heretofore been the practice to open the flue door and to rake out the soot allowing the same to fall on the floor at the front of the furnace or upon 15 some means placed on the floor. With this method the soot is distributed about in the air and a great deal of it is deposited on the clothing of the operator and inhaled into the lungs. Sometimes it is attempted 20 to rake the soot into a shovel, but a great deal of the soot is not received therein, and drops to the floor or flies about. Furthermore, the soot scatters about on the floor and if it is merely dropped on the floor it 25 is extremely difficult to shovel up and remove. The result is that this soot is often tracked by the operator into other parts of the building and floors and carpets of dwellings are thus frequently soiled and damaged. 30

It is an object of this invention, therefore, to provide a device by means of which the soot may be collected immediately adjacent the flue door and so retained in said device that it is not scattered about in the air or 35 on the floor and can be conveniently disposed where desired.

It is a further object of the invention to provide such a device in the form of a receptacle having means adapted to be disposed under the door opening and further means adapted to hold the receptacle in such 40 position.

It is more specifically an object of the invention to provide such a receptacle substantially of V-shape in vertical cross section and having adjustable means, preferably resilient, adapted to engage the sides 45

of the door opening to hold the receptacle in position below the same. These and other objects and advantages of the invention will 55 be fully set forth in the following description made in connection with the accompanying drawings in which like reference characters refer to the same parts throughout the different views; and in which— 60

Fig. 1 is a view in vertical section through a portion of the furnace and through the device of the invention showing the latter in operative position; and

Fig. 2 is a top plan view of the device, 65 a portion of the furnace being indicated in dotted lines.

Referring to the drawings, in Fig. 1 is shown a portion of a common type of heating furnace having the casing wall 1, the 70 door frame 2 having the usual front opening therein which is normally closed by the door 3 hinged at one side of the said opening. The door frame is often made as a separate casting and bolted or riveted to the 75 furnace casing, but for convenience, the same is shown in the drawings as integral with the casing. The door frame 2 is also provided with an inwardly extending flange 4 extending thereabout, the outer side of 80 which forms a surface against which the edge of the door 3 contacts. The flue or hot water chambers are diagrammatically shown as 6 in Fig. 1.

The device of the present invention comprises a receptacle 7 which will be made of sheet material, preferably metal, and which, as illustrated, is provided with a rounded or reinforced edge. Said receptacle, as clearly shown in Fig. 1, is provided with a rear 85 wall which slopes downwardly and outwardly from the furnace, the outer or front wall of said receptacle being shown as substantially vertical so that the receptacle is substantially of V-shape in vertical cross 90 section although the invention is not limited to this particular shape. Also, as clearly shown in Fig. 2, the receptacle is substantially of rectangular shape in horizontal cross section, although this shape of the receptacle may also be varied. The rear edge 95 8 of the receptacle is adapted to extend across the front of the furnace beneath the edge of the door casing and the receptacle 100

is held in position below the door opening by means illustrated as comprising a pair of members 9. In the embodiment of the invention illustrated, these members comprise 5 clips formed of flat sheet material, preferably metal, and also preferably resilient, provided with out-turned hook portions at their outer ends, which ends extend substantially in vertical planes. Said clips are 10 bent diagonally so that the inner portion thereof extends substantially in a horizontal plane and this inner portion is bent around a rod 10 extending across the receptacle 7 and having its ends journaled in the end 15 walls thereof. The bent end of the clips 9 is riveted so as to permanently enclose the rod 10 and the clips are slidable longitudinally on said rod. Said rod, as shown, is 20 of angular or squared cross section so that the clips 9 cannot rotate thereon but must rotate therewith and said rod is provided at one end with a loop member 11 having its ends extending, one inside and one outside of the receptacle, which ends are bent 25 about the rod to hold the same in position therein. This member 11 forms a stop engaging the rear and end edges of the receptacle 7 to limit the rotating movement of the rod 10 and said loop also forms a handle 30 which may be engaged by the fingers to rotate said rod when desired. The receptacle also is preferably provided with a convenient handle 12 bolted to the front wall shown as of the common bail type but 35 which may be of any suitable form.

In operation, the receptacle is placed in 40 position, as shown in Fig. 1, with its rear edge under the door casing 2. This door is, as shown, the flue or cleanout door generally located above the fire door. With the front 45 edge disposed as shown, the rod 10 is rotated by throwing over the loop 11 to bring the clips 9 extending forwardly into the opening of the door. Said clips are then slid laterally to engage the sides of the door frame, 50 as shown in the drawings. The clip 9 can only be moved by engaging the same close to the rod 10 and if moved at the outer ends will tend to rotate and bind on the rod and 55 will have considerable resilient movement. These clips can thus be brought into firm engagement with the sides of the door opening, and will firmly and resiliently engage the same. The hooks of the clips will also 60 engage back of the flange 4 and thus further insure that the receptacle will be firmly held in position. With the receptacle so positioned, the soot, dirt, rust, etc., can be scraped forward from the members 6 and 65 the same will be drawn through the door opening and fall immediately into the receptacle 7. This soot and dirt will thus not be dropped downward to be distributed in the air or to fall upon the floor. After the soot 70 has been raked into the receptacle, the same

can be quickly removed by a slight sliding movement of the clips 9 and the receptacle carried to the point where it is desired to deposit the soot. Such soot, as is well known, is not heavy and the receptacle can be conveniently carried in one hand by means of the handle 12.

From the above description it is seen that applicant has provided an extremely simple and efficient means for collecting the soot 75 and other matter removed through the flue door of a furnace. The device is extremely easy to operate and can be easily and inexpensively made and the same will, as is evident, be very durable. In practice, the device will preferably be made from some 80 non-corrosive metal or material having a non-corrosive coating.

It will, of course, be understood that various changes may be made in the form, details and proportions of the device without departing from the scope of applicant's invention, which, generally stated, consists in the matter shown and described and set forth in the appended claims.

What is claimed is:

1. A device for collecting soot and dirt removed through a furnace door, comprising a comparatively deep receptacle adapted to be disposed against the front of the furnace, having means constructed and arranged to be disposed beneath and engaging the under side of the door casing of said furnace, and having spaced means constructed and arranged to project into the door casing, said latter means projecting laterally in opposite directions to engage the interior of the door frame.

2. The structure set forth in claim 1, said receptacle being of substantially V-shape in 105 vertical cross section, and having a substantially horizontal top edge, the wall thereof adjacent the furnace being adapted to extend outwardly and downwardly.

3. A device for collecting soot and dirt removed through a furnace door, comprising a comparatively deep receptacle adapted to be disposed against the front of the furnace, having means constructed and arranged to be disposed beneath and engaging 115 the under side of the door casing of said furnace, a member extending across said receptacle adjacent the top edge thereof and resilient clips slidable on said member, said clips having hook portions extending outwardly and adapted to project through the door opening and engage the interior of the door frame.

4. A device for collecting soot and dirt removed through a furnace door opening 125 comprising a receptacle adapted to be disposed below the door opening a rod journaled in said receptacle and extending transversely thereof, flat angularly bent clips slidable on said rod and rotatable therewith 130

having hooked end portions adapted to engage the sides of the door opening, and a handle and stop member on said rod.

5. A device for collecting soot and dirt, comprising, a receptacle adapted to be disposed with its edge below the door opening of a furnace, a rod journaled in said receptacle and extending transversely thereof, and

being of angular cross section in said receptacle, and a pair of clips slideable on said rod 10 and adapted to extend through the door opening and engage the sides thereof to hold the receptacle in position.

In testimony whereof I affix my signature.

PAUL W. THAYER.
